UNITED STATES PATENT OFFICE.

PAUL J. SAXER, OF LOS ANGELES, CALIFORNIA.

MOVABLE BALL RACK FOR POCKET-BILLIARD TABLES.

Application filed October 6, 1921. Serial No. 505,780.

To all whom it may concern:

Be it known that I, PAUL J. SAXER, a citizen of the United States, residing at Los Angeles, in the county of Los Angeles and State of California, have invented new and useful Improvements in Movable Ball Racks for Pocket-Billiard Tables, of which the following is a specification.

My invention relates to a ball receiving rack for pocket billiard tables; the principal objects of my invention being to provide a relatively simple and practical ball receiving rack that may be conveniently arranged on the end or side of a pocket billiard table, to provide a mounting or support for the rack that will permit the latter to be readily shifted from one position to another to enable the players to easily and conveniently make their shots from any point around the rail of the table; further to provide a ball receiving rack that may be readily swung into position to effect a simultaneous discharge of the contained balls onto the surface of the table; to provide a construction that may be swung into position whereby the balls may be readily counted, to provide a construction that will eliminate the use of the ordinary wall racks now in general use; and further to provide a device that will eliminate the services of an attendant or employee whose duties are to transfer the balls from a wall rack to the surface of the playing table and consequently effecting the saving of time, labor and consequent expense.

With the foregoing and other objects in view, my invention consists in certain novel features of construction and arrangement of parts that will be hereinafter more fully described and claimed and illustrated in the accompanying drawings, in which:

Figure 1 is an end elevational view of a pocket billiard table that is equipped with a ball receiving rack of my improved construction.

Fig. 2 is a top plan view of a portion of my improved ball receiving rack.

Fig. 3 is an end elevational view of the rack embodying my invention, and showing the same in position upon a table.

Fig. 4 is an elevational view showing the rack swung upwardly into position to effect a discharge of the balls onto the surface of the playing table.

Fig. 5 is an elevational view of a hinge

that is utilized as a connection between the ball supporting rack and the table.

Fig. 6 is a vertical section taken approximately on the line 6—6 of Fig. 5.

Fig. 7 is a detail view of a modified form 60 of the sliding hanger or support for my improved ball receiving rack.

Referring by numerals to the accompanying drawings which illustrate a practical embodiment of my invention, 10 designates 65 the bed or body of a pocket billiard table, 11 the marginal rail on the top of the table and which rail serves as a support for the cues in playing the game, and 12 the pockets that are arranged at the corners of the table 70 and at intermediate points on the sides thereof, and which are adapted to receive the balls used in playing the game.

The support for the ball receiving rack is preferably in the form of a metal rod 13 75 that is positioned on the side or end of the bed or body of the table a short distance below the rail 11 thereof, and said rod being secured to the body of the table by suitable brackets 14.

The frame of the rack comprises a top plate 15 of wood or metal, a bottom plate 16 of wood or metal, and the corners of which plate are connected by pairs of inclined rods 17, the ends thereof being secured to the plates 15 and 16 in any suitable manner. Inasmuch as the rods 17 are inclined, the bottom plate 16 is offset with respect to the top plate 15, and thus the rack occupies an inclined position that is substantially parallel with the outer face of the side or end of the table body. As a result of such construction, the rack occupies an out of the way position beneath the top rail 11, and as the supporting member 13 extends 95 the entire length or width of the table, the rack may be readily shifted from one position to another on said supporting rail so that it does not interfere with the movements of the player while making a shot.

Formed in the upper plate 15 is a series of four or more ball receiving openings 18, and appearing adjacent to each opening and preferably at diametrically opposite points on the upper face of said plate 15 are designating numerals preferably arranged in consecutive order, and which are of material assistance to the players in keeping proper score of the game. Seated in the top plate 15 and disposed about each open- 100 105 110

ing 18 are the upper ends of a series of ball supporting members 19 of wood, wire or other suitable material, and which are bent to form sinusoidal curves, and 5 which arrangement tends to restrict the rolling movement of the balls lengthwise through the chambers or spaces between said supporting members. In addition to being inclined inwardly from top plate 15 to bottom plate 16, the supporting members 19 are 10 all inclined laterally, as illustrated in Fig. 1, and which arrangement greatly facilitates the discharge of the balls from the rack when the same is swung upwardly with plate 15 positioned above the rail 11 of the table, as illustrated in Fig. 4.

To provide a rolling support for the lower portion of the rack, brackets 20 carrying rollers 21 project inwardly from lower plate 20 16, and said rollers bear directly against a track rail 22 that is positioned on the outer face of the table a short distance below the supporting member 13. To support the weight of the movable ball receiving rack 23 and the balls positioned therein, a vertically disposed supporting member 22^a depends from the lower member 16 and the lower end of said member carrying a suitable caster wheel 22^b, and which latter is adapted to 30 ride directly over the floor upon which the table is positioned. This member 22^a may also serve as a brace when the rack is swung upward to permit the balls to be counted.

To support the rack when the same is 35 swung outwardly away from the body of the table when the balls are to be counted, an arm 23 is pivotally connected at its upper end to a bracket 24, which latter is supported by the rear or inner pair of rods 17, and the lower end of said pivoted arm is adapted to engage upon teeth 25 that project outwardly from a plate 26, and the latter being secured to the bed or table 10 a short 40 distance above track rail 22.

45 The means for connecting the upper plate 15 to the supporting rail 13 comprises hinge members 27 that are directly connected to the rear edge of plate 15, and pivotally connected to the upper ends of said hinge members 28 that are depending hinge members 28 that are substantially longer than said members 27.

The lower ends of said members 28 are 50 pivotally connected to vertically disposed hinge members 29, the upper portions of which extend a substantial distance above the upper ends of members 28, and journaled on pins 30 that are seated in the upper ends of said members 29 are grooved rollers 31 that ride directly on top of rail 13.

Secured on the upper portions of members 29 and on the inner faces thereof are pins 32 on which are journaled grooved rollers 33, the same occupying positions immediately below the grooved rollers 31, and which

construction retains the supporting members in position upon the rail 13 when the rack is swung upward into position to discharge the balls onto the table (see Fig. 4).

Pivots connected to the hinge pin between the parts 27 and 28 is a hook 34 that normally engages over the supporting rail 13, as illustrated in Figs. 3 and 6, thereby retaining the hinge parts 27 and 28 and the upper portion of the rack in position immediately adjacent to the rail 13. 75

The ends of top plate 15 are beveled or inclined, and pivotally connected to said beveled or inclined ends are the upper ends of arms 35 which normally hang downward and outward, as illustrated in Fig. 1, and which arms are adapted to be swung over onto the upper surface of the table when the rack is shifted into position to discharge the balls onto the table, and thus said arms 80 serve as retaining and guiding members to prevent the balls from rolling to various parts of the table when discharged thereonto. This arrangement is effective in maintaining the balls in a relatively small area, 85 and consequently effecting a saving of time and labor in placing the balls in the triangular rack that is utilized for properly positioning the balls on the table. 90

Arranged on the under side of top member 15 and preferably adjacent to its outer edge is a ball retaining device 36 that may be formed from a strip of wood, or an elongated section of metal, such as wire, the end portions of said member being pivotally connected to suitable brackets, such as 37, that depend from the under side of member 15 adjacent to its ends. Portions of the member 36 are extended downwardly to form ears or lugs 38, and which latter are 100 spaced so that when the member is swung inwardly and upwardly, said ears will extend into the channels formed between the ball retaining members 19, and consequently preventing the balls from rolling out of the 105 rack when the latter is swung outward and upward into position to count the balls. 110

Under normal conditions the rack occupies the positions, as illustrated in Figs. 1 and 3, and when so positioned the rack may 115 be shifted from one side of the table to the other so that it will not interfere with the movements of the players while making their shots. As the balls are pocketed during the playing of the game, the players remove their pocketed balls and drop the same through the openings 18 in top member 15 of the rack, it being understood that each player, prior to the beginning of the game, selects one of the numbered compartments in the rack in which to place the pocketed balls. As the balls are inserted through openings 18 they will pass downwardly through the sinusoidal channels formed between the members 19, and the 120 125 130

particular shape of members 19 restricts or retards the rolling movement of the balls into the lower portion of the rack.

At the termination of the game, or when 5 it is desired to count the balls pocketed by the respective players, the lower portion of the rack is engaged and drawn outwardly and upwardly, thereby swinging the rack outwardly and upwardly away from its normal position adjacent to the bed of the table, and when so positioned the balls and the numbers thereupon may be readily counted.

When it is desired to discharge the balls 10 from the rack onto the surface of the playing table, the rack is swung upwardly into a slightly inclined position with the upper member 15 positioned directly above the rail 11 of the table, as illustrated in Fig. 4, and when so positioned the balls contained 15 within the rack will gradually discharge therefrom by rolling downwardly between the sinusoidal members 19. It will be understood that to permit the balls to discharge from the rack, it is of course necessary to manually rotate the retaining device 20 36 so that the lugs 38 are moved inwardly and clear of the openings 18. To prevent the balls from spreading over the surface of the table, the arms 35 are swung downwardly onto the surface of the table, thereby forming inclined guard rails that retain the entire series of balls within a relatively small compass, and enabling said balls to 25 be readily placed in the triangular rack ordinarily used for assembling and spotting balls. When the rack is swung upwardly to effect a discharge of the balls, the hook 34 becomes disengaged from supporting member 11, and the parts of the hinges that 30 connect the upper portion of the rack to supporting member 13 swing into the positions, as shown in Fig. 4.

In the modified construction illustrated 35 in Fig. 7, short vertically disposed rods 38 provide hangers for supporting the movable ball receiving rack, said rods being provided at their upper ends with hooks 39 that engage over the rail or supporting member 13, and the lower ends of said 40 hangers being provided with antifriction rollers 40 which are adapted to bear against the outer face of the bed of the table. Portions of the hanger rods adjacent to their upper ends are bent outwardly to form 45 notches 41, and which latter receive screw eyes, or like members 42, that are seated in and project rearwardly from the top member 15 of the rack. Where this construction is utilized, the hooks 39 in the upper ends 50 of hangers 38 slide lengthwise upon the supporting rod 13 when the rack is shifted from one position to another, and which construction also enables the rack to be 55 swung outwardly and upwardly away from the table in order that the balls may be 60

counted or discharged onto the top of the table.

Thus it will be seen that I have produced a ball rack for pocket billiard tables that will conveniently receive and hold the balls 70 at a point immediately adjacent to the table, said rack being movable from one position to another so that the players may move freely along the rails of the table in making their shots, said rack normally occupying 75 an out of the way position below the top rail of the table, and said rack being mounted so that it may be swung upward to enable the balls to be counted, and also for the purpose of permitting the balls to discharge 80 onto the surface of the playing table.

The rack is of relatively simple structure, may be easily and cheaply produced, eliminates the use of the usual wall rack associated with pocket billiard tables, and is effective 85 in saving much of the time and labor ordinarily involved in the handling of the balls, particularly in assembling the same for play upon the table.

It will be understood that minor changes 90 in size, form and construction of the various parts of my improved pocket billiard table rack may be made and substituted for those herein shown and described without departing from the spirit of my invention, the 95 scope of which is set forth in the appended claims.

I claim as my invention:

1. A ball rack comprising a ball supporting frame, means adapted to support the frame for horizontal movement upon a table, and means for connecting the frame to said means to permit of the frame being swung upwardly in overlying position with respect to the table to discharge the balls in 100 the frame on the table.

2. A ball rack comprising a ball supporting frame, means adapted to support the frame at one side of a table, and pivoted means for extensibly supporting the frame 110 to allow of the frame being moved to overlying position with respect to the table to discharge the balls in the frame on the table.

3. In combination, a ball receiving rack mounted to occupy ball receiving and ball discharging positions, and likewise means for preventing the balls from discharging from the rack when the latter is moved to ball discharging position.

4. A ball rack comprising a support, a ball supporting frame arranged for horizontal sliding movement on said support, and means for extensibly associating the frame with the support to permit upward and outward swinging movement of the frame.

5. The combination with a pocket billiard table, of a ball receiving rack arranged for movement on the table, and a support for the rack depending therefrom and adapted to have rolling engagement with the floor.

- 4
6. A ball rack comprising a frame, means for hingedly supporting the frame whereby the latter is capable of being swung upwardly and outwardly with respect to the side of a table, and means for supporting the first means for horizontal adjustment.
7. The combination with a pocket billiard table having a pair of horizontally disposed supporting rails on one of its side faces, of a ball receiving rack arranged for movement upon said spaced rails.
8. A ball rack comprising a pair of horizontally disposed supporting rails, a frame arranged for movement along the rails, and means for supporting the frame to permit of an upward, outward and inward swinging movement thereof.
9. A ball rack for pocket billiard tables having a series of vertical compartments arranged one beside the other, and ball retarding members within said compartments.
10. A ball receiving rack for pocket billiard tables comprising an upper member having openings adapted to receive balls, a lower member, and a series of inclined members arranged between said upper and lower members and forming elongated ball receiving pockets.
11. A ball receiving rack for pocket billiard tables provided with a series of ball receiving compartments that are separated by sinusoidal members.
12. A ball receiving rack for pocket billiard tables provided with a series of ball receiving compartments that are separated by inclined sinusoidal rods.
13. A ball receiving rack for pocket billiard tables comprising a skeleton frame, the upper member of which is provided with ball receiving openings, and sinusoidal rods extending downwardly through the frame between said openings.
14. A ball receiving rack for pocket billiard tables comprising a skeleton frame, the upper member of which is provided with
- ball receiving openings, and inclined sinusoidal members extending downwardly through the frame between said openings.
15. The combination with a pocket billiard table, of a ball receiving rack having a plurality of ball chambers, which rack is mounted so as to be swung outwardly and upwardly with respect to the table to which it is connected, and means associated with said rack for preventing the balls from discharging from the rack when the same is swung outwardly and upwardly.
16. The combination with a pocket billiard table, of a movable ball rack connected thereto so as to be swung outwardly and upwardly with respect to the rail of said table, to occupy a ball discharging position and means carried by the upper portion of said rack for guiding the balls as they discharge from the pockets in said rack.
17. A ball rack, means for mounting the rack for horizontal adjustment, and means associated with the last means for sustaining the rack for vertical swinging movement.
18. In combination, a pocket billiard table, a ball supporting rack constructed to occupy a position in which it is disposed in spaced parallelism to one inclined side of said table, and means for supporting the rack to occupy ball receiving and discharging positions.
19. In combination, a pocket billiard table, a ball supporting rack constructed to occupy a position in which it is disposed in spaced parallelism to one inclined side of said table, means for supporting the rack to occupy ball receiving and discharging positions, and means associated with the first means to permit of a horizontal adjustment of the rack with respect to the table.

In testimony whereof I have signed my name to this specification.

PAUL J. SAXER.
